MEASURING DEVICE

Lewis M. McCormick, Palo Alto, Calif., assignor to
 The Scholl Mfg. Co., Inc., Chicago, Ill., a corporation of New York

Application June 30, 1941, Serial No. 400,447

1 Claim. (Cl. 33—3)

This invention relates to improvements in a measuring device, and more particularly to a measuring device highly desirable for use in measuring the feet or other extremities of the body to denote the size of some appliance to be attached to the foot or other extremity, although the invention may have other uses and purposes as will be apparent to one skilled in the art.

In the past, the common and generally accepted way of denoting the size of a foot has been by way of reference to the size of shoe fitting that foot. While this procedure gives in general an approximation of reasonable accuracy as to size, it falls far short of being sufficiently accurate to denote the proper size of an appliance to be attached to the foot or associated with the foot, especially when the appliance is in the nature of a foot corrective appliance for disposition within a shoe. Many such corrective appliances are intimately attached to the naked foot, attached to the foot outside of the hosiery, or placed within a shoe for the foot to press against. In either event, it is highly desirable and sometimes essential to have the proper size of corrective appliance to more than just a reasonable degree of exactness. Feet vary in width and length to such a considerable extent, that a treatment appliance for application to a particular part of a foot cannot be selected for fit with the desired degree of accuracy merely by reliance upon the size of shoe commonly worn by the particular patient.

With the foregoing in mind, it is an important object of the present invention to provide a measuring device capable of readily and easily giving the exact size of a corrective appliance to properly fit a particular foot or other extremity.

It is also an object of this invention to provide a measuring device so shaped as to intimately fit the part of the foot or other extremity being measured.

Still a further object of this invention is the provision of a measuring device highly desirable for measuring the human foot and capable of indicating the proper size of a corrective appliance to be applied to the foot, the measuring device being shaped in keeping with the corrective appliance to be used and fitting the foot in the same manner as the ultimate corrective appliance will fit the foot, thereby giving an accurate size for the corrective appliance.

Still a further feature of the invention is the provision of a foot measuring device shaped to fit around the human foot in the region of the metatarsal arch, the device not only carrying proper size indicia but also being shaped to fit

10 a projection of the foot, such as the first metatarsal head, to insure accurate positioning of the device during use.

While some of the more salient features, characteristics and advantages of the present invention have been above pointed out, others will become apparent from the following disclosures, taken in conjunction with the accompanying drawing, in which—

Figure 1 is a fragmentary plan view of a measuring device embodying principles of the present invention;

Figure 2 is a reduced fragmentary plan view illustrating the device of Fig. 1 in use in measuring a part of the human foot; and

Figure 3 is a fragmentary plan view showing a corrective appliance in position on the human foot, the size of which appliance has been accurately determined by the use of the present invention as indicated in Fig. 2.

As shown on the drawing:

In the illustrated embodiment of this invention there is shown a measuring device in the form of a tape or the equivalent, generally indicated by numeral 5, and which may be made of paper, fabric, leather, or any other suitable material.

One end portion 6 of the tape may be provided with any suitable indicia or advertising material, such as the illustration 7 indicating the proper use of the device. Near this end 6 of the tape is suitable base indicia, which may be in the nature of a starting line 8. Inside of the base line 8 the tape is preferably widened as indicated at 9 and this portion of the tape is preferably provided with a suitable aperture or opening 10, preferably generally egg-shaped, which aperture is centrally disposed to leave a solid band on each side thereof. When used as a foot measuring device, especially for transverse measurement in the region of the metatarsal arch, the opening 10 is preferably sized to accommodate the first metatarsal head or big toe joint 11 of a foot 12, as indicated more particularly in Fig. 2. A band portion of the tape will be disposed on each side of the protruding metatarsal head 11, and thus the tape is positively held in the correct position for taking the measurement.

On the opposite side of the widened portion 9 from the base line 8, the tape is reduced in width and extends in the form of a relatively narrow elongated portion 13 which is preferably narrower than the end portion 6 and which carries thereon a series of size indicating indicia 14. Each size indicium preferably has associated therewith a line 15 extending transversely across

the tape for registry with the aforesaid base line 8 in taking a measurement.

In use, it is a simple expedient to place the tape around the anterior portion of the foot as indicated in Fig. 2. The end portion 6 is preferably laid on the top of the foot so that the base line 8 is disposed adjacent the second metatarsal head. The tape is then brought around and beneath the foot so that the opening 10 is occupied by the first metatarsal head, as above explained. The elongated portion 13 of the tape extends beneath the foot, and around the outside of the foot adjacent the fifth metatarsal head, thence, over the top of the foot until one of the lines 15 registers with the base line 8. When one of the lines 15 registers with the base line 8 after the tape has been drawn snugly, but preferably not tightly, around the foot, the number associated with that particular line 15 denotes the size of appliance to correctly fit that particular foot. In denoting such size, the line 15 on both sides of its size number should coincide or register evenly with the base line 8. Of course, when the tape is properly positioned and drawn snugly about the foot, if no line 15 registers exactly with the base line 8, a half size may be indicated, although for most purposes half sizes would not be necessary.

The particular form of the invention illustrated in the drawing and described hereinabove is highly desirable for indicating the proper size of a correction appliance such as that illustrated, described and claimed in Lewis M. McCormick Letters Patent No. 1,898,092, entitled "Arch support retainer," issued February 21, 1933. In Fig. 3 I have illustrated such a corrective appliance in position on the foot 12, and it will be seen that the appliance includes a relatively narrow band portion 16 extending across the top of the foot. Adjacent this band portion 16 the device is split into two spaced band portions 17 and 18 defining an aperture 19 therebetween for the reception of the first metatarsal head 11 in the same manner as above described in connection with the measuring device. On the opposite side of the band portion 16 the device continues around the fifth metatarsal head as indicated at 20 and on the underside of the foot a suitable metatarsal arch supporting pad (not illustrated) may be incorporated in the appliance.

It will be noted that the shape of the measuring device is in keeping with the shape of the cor-

rective appliance illustrated in Fig. 3 so that when placed in position on the foot to take a measurement, the measuring device fits the foot in substantially the same manner as does the ultimate corrective appliance, and therefore the proper and exact size of corrective appliance to be used is designated by the measuring device.

It will be appreciated that the measuring device may be varied somewhat in shape in the event a different form of corrective appliance is to be used.

From the foregoing, it is apparent that I have provided a novel foot measuring device, highly desirable for use in connection with the indication of the proper size of a foot corrective appliance to be used with a particular foot, the device giving an accurate measurement in keeping with the subsequent fit of the corrective appliance, being simple in construction, economical to manufacture, and usable with great facility.

It will, of course, be understood that various details of construction may be varied through a wide range without departing from the principles of this invention and it is, therefore, not the purpose to limit the patent granted hereon otherwise than necessitated by the scope of the appended claim.

I claim as my invention:

A device adapted for measuring a human foot in the region of the metatarsal arch which comprises a tape of a length to more than encircle the foot transversely, said tape having an intermediate portion defining an aperture adapted to receive the big toe joint of a human foot, a first end portion extending from one end of said intermediate portion adapted to extend over the top of the foot when the intermediate portion is fitted around the big toe joint and a second end portion extending from the other end of the intermediate portion adapted to be wrapped under and over the foot to overlie the first end portion, said second end portion being narrower than the first end portion, a base marking indicia on the first end portion adapted to project laterally on beyond the second end portion when the latter is superimposed thereon, and a series of size indicia on the second end portion for cooperating with the base indicia to indicate the size of the foot portion being measured.

LEWIS M. McCORMICK.
